Cressell & Davis

UNITED STATES PATENT OFFICE.

GEORGE E. HERRMANN, OF MORRISTOWN, AND BENJAMIN W. TUCKER, OF SOUTH ORANGE, NEW JERSEY; SAID TUCKER ASSIGNOR TO SAID HERRMANN.

BARREL.

1,281,568.

Specification of Letters Patent. Patented Oct. 15, 1918.

Original application filed February 17, 1912, Serial No. 678,344. (Patent No. 1,216,808, dated February 20, 1917.) Divided and this application filed December 30, 1916, Serial No. 139,777.

To all whom it may concern:

Be it known that we, GEORGE E. HERRMANN and BENJAMIN W. TUCKER, citizens of the United States, and residents of Morris-
5 town, county of Morris, State of New Jersey, and South Orange, county of Essex, and State of New Jersey, respectively, have invented certain new and useful Improvements in Barrels, of which the following is a specification.

This invention relates more particularly to barrels made of sheet steel.

The principal object of the invention is to provide simple and efficient means for locking the barrel head or heads to the staves or members and for strengthening the barrel or container at its ends.

A still further object of the invention is to provide a barrel which is inexpensive to manufacture and which may be readily made and assembled.

With these and other objects in view, the invention will be hereinafter more particularly described with reference to the accompanying drawings, which form a part of this specification, and will be then pointed out in the claims at the end of the description.

In the drawings, Figure 1 is a side elevation, partly broken away and partly in section, of one form of barrel embodying our invention.

Fig. 2 is a plan view partly broken away and partly in section.

Fig. 3 is a detail perspective view of one of the barrel staves or members;

Fig. 4 an enlarged fragmentary section, showing one means for locking the head and staves or members together; and Fig. 5 shows different means for holding the ends 40 of the barrel staves or members and the barrel heads together.

This application is a division of our Patent No. 1,216,808, dated February 20, 1917.

While the invention is shown as applied more particularly to a barrel having a bilged or enlarged central portion, it will be understood that the invention may be applied to other forms of barrels or other containers.

The barrel body 10 comprises a plurality of staves or members 11. These staves or members may be variously constructed and may be curved and bilged centrally to make the barrel larger at its central portion than at its ends in order that the barrel may be handled

in a manner similar to that of the ordinary 55 wooden barrel. Each stave or member 11 has a flange 12 along one edge and a flange 13 along its other edge. These flanges extend the greater part of the length of the staves or members, and the flange 12 is provided 60 with a tongue or rib 14 extending throughout the entire length thereof; and the flange 13 is provided with a depressed portion forming a groove 15 lengthwise thereof. Each flange has an inwardly extending part 65, 17 in order to prevent injury to the objects or material contained within the barrel, and said parts 17 may extend inwardly toward the body of the stave or be otherwise formed as desired. The tongue or rib 14 of the 70 flange 12 is adapted to fit into the groove 15 of the flange 13 of the next adjacent stave, thus serving to cause the flanges to interlock throughout substantially their entire length.

A head 20 may be located at either or both 75 ends of the barrel body and each head is provided with an outwardly projecting flange 21 having an annular groove 22 located substantially midway between the outer edge of the flange and the body of the 80 head. The heads 20 each have their body portions resting upon shoulders 23 formed by the ends of the flanges 12 and 13, and each head has its outer edge resting against the offset portion 24 of the staves or members, the latter terminating in substantially straight portions 25 at its ends, which are adapted to lie against the flanges 21 of the heads 20. The straight portion or end 25 of each stave is provided with a rib or tongue 90 26 which, when the staves or members are placed together, form a substantially continuous rib which is adapted to enter the groove 22 of the flange 21. The flange 21 of each head 20, and the ends of the staves 95 or members, enter an annular channel formed between the vertical walls 27 and 28 of a split band or compression member. The wall 27 is slightly angular so as to lie closely against the inner surface of the flange 21, 100 and has its inner edge resting against the outer surface of the head 20, and said walls 27 and 28 are joined together by an integral horizontal portion 29. The wall 28 of the split band is provided with an annular 105 grooved portion forming an internal bead or rib 30 which is adapted to fit into the groove formed by the tongues or ribs 26 of the

staves or members. A wire tightening band or element 31 is located in the annular groove formed by the rib 30 of the compression member, and the wall 28 of said member is offset, at 32, and terminates in the skirt portion 33 extending a short distance along the staves or members lengthwise thereof. A second tightening wire or band 34 is arranged under the offset portion 32 so that when the bands 31 and 34 are tightened by twisting the ends thereof or otherwise, the split ring will be compressed, thereby rigidly binding and holding the heads and members together and at the same time strengthening the ends of the barrel or container.

The staves or members are depressed transversely at 35, intermediate the ends thereof, to provide annular grooves when the members are put together. A wire or element 36 is located in each of the grooves formed by the depressed parts 35, so that when these wires are tightened by having their ends twisted or otherwise, the body 10 of the barrel or container will be rigidly and effectively bound together intermediate the ends.

In Fig. 5, the body 38 may be of any suitable construction and may comprise a plurality of members constructed as already described. The staves or members may be depressed transversely to form a grooved portion 39 against which is adapted to rest the edge of one of the heads 40. Each head 40 has an outwardly projecting flange 41, and the outer ends 42 of the staves or members may be straight and are adapted to lie against the outer surface of the flange 41. The part 42 and the flange 41 of the head 40 may be provided with apertures spaced apart, and passing through these apertures may be a suitable fastener. As shown, an ordinary paper fastener is provided for this purpose, there being a series of these fasteners varying in number as desired and each having a head portion 43 with the bendable ends 44 which are adapted to be passed through the openings in the ends of the staves or members and the flange 41 of the head, and then bent along said flange on the inner surface thereof in the manner shown, thus holding the members and heads together. A divided or other band or member 46 is provided. This band is compressible and has its outer part hook-shaped to form a channel to receive the flange 41 and the ends of the barrel staves, and said hook-shaped part may be formed by a flange 47

and a flange 48, the latter lying parallel with the flange 41 of the barrel head 40 and within the same so that its inner edge will rest against the outer surface of the head. The flange 47 of the member or band 46 may have its skirt portion 49 extending inward along the barrel members for a short distance, and may have a ribbed or beaded portion 50 forming an annular groove, the said portion being adapted to enter the grooved ribbed portion 39 of the members. A wire band or element 51 is located in the groove 50, and when its ends are bound together by twisting or otherwise, the band 46 may be compressed so as to hold the head and staves or members together, and further to strengthen the ends of the barrel.

From the foregoing it will be seen that simple and efficient means has been provided for rigidly binding the staves or body members of the barrel to the head; that means has been provided for protecting the ends of the staves from being crushed or bent; and that simple means has been provided for locking the staves and heads together to prevent relative vertical movement thereof.

What we claim is:

1. A barrel or other container comprising a plurality of members having transversely extending ribs at their outer ends, a head having an annular groove to receive said grooved ribs, a divided band having an offset portion and provided with a grooved annular rib adapted to enter the grooved ribs of the members, and wire bands fitting about the offset portion of the divided band or member and the grooved ribbed portion to hold the ends of the members and heads together.

2. A barrel or other container comprising a plurality of members having transversely extending ribs at their outer ends, a head having a flange provided with an annular groove to receive said grooved ribs, an annular compression member having an offset portion and provided with a grooved annular rib adapted to enter the grooved ribs of the members, and two wire bands fitting about the offset portion of the compression member and the grooved ribbed portion to hold the ends of the members and heads together.

In testimony whereof we hereunto affix our signatures this 29th day of December, 1916.

GEORGE E. HERRMANN.
BENJAMIN W. TUCKER.
